UNITED STATES PATENT OFFICE.

EDWIN SCHUETTE, OF MANITOWOC, WISCONSIN.

CHART FOR RECORDING-COMPASSSES.

939,867.

Specification of Letters Patent.

Patented Nov. 9, 1909.

Original application filed June 22, 1908, Serial No. 441,892. Divided and this application filed May 27, 1909.
Serial No. 498,766.

To all whom it may concern:

Be it known that I, EDWIN SCHUETTE, of Manitowoc, Wisconsin, have invented a Chart for Recording-Compasses, of which 5 the following is a specification.

This invention is a chart or schedule for making continuous records of the steering direction of a ship, such as may be made by the automatic action of the recording-pen or 10 pencil of a registering-apparatus.

The object of the present invention is to provide a scheme for placing in a single line 15 all of the compass-rhumbs without breaking the continuity of the arrangement in passing from one compass-point to the next; so that they can be recorded by the continuous movement of the recording-point, and without breaking continuity as would be occasioned were it necessary for the recording- 20 point to skip from one edge of the chart to the opposite edge, as has been the case in some schemes heretofore devised.

The principle of my invention lies in the arrangement of separate rhumbs or compass 25 directions on opposite sides of a given diametral line, ordinarily the lubber-line or north-south diameter, in such a manner that symmetrical points with respect to said line are placed adjacent and in alternate relation 30 in proceeding from one pole of said line to the opposite one.

This application is a division of the United States application No. 441,892, filed 35 June 22, 1908, for a recording - compass, jointly by myself and Nicholas Dedrick.

In the drawings hereto annexed, Figure 1 shows a scheme for a recording-chart in which only the full points, or ordinary 32 rhumbs, are used, and provided with curved 40 lines for the swinging recording-point illustrated by our aforesaid patent, showing a portion of a sailing-record thereon; and Fig. 2 shows a fragmentary portion of a chart in which quarter - rhumbs are used, and de- 45 signed for a recording-instrument whose recording-point moves in a straight line.

In these drawings the same part is designated by the same reference-letter in each figure.

50 It will be understood that this kind of chart comprises a roll of indefinite length on which the compass-record is inscribed, and in which the longitudinal element of direction represents time and the transverse

element the direction in which the vessel is 55 headed.

As will be seen from the drawing, the north and south rhumbs are placed at opposite edges of the chart, and the rhumbs which are on either side thereof in the compass are 60 arranged in alternate directions proceeding in regular order from one to the other; so that north, for example, is followed by north-by-east, north-by-west, north-north- 65 east, north-north-west, etc., successively; or where the directions are divided more minutely, as in Fig. 2, the direction north is followed successively by north-quarter-east, 70 north-quarter-west, north-half-east, north-half-west, north-three-quarter-east, north- 75 three-quarter-west, north-by-east, north-by-west, etc. For the sake of distinguishing the east and west directions readily by the eye and projecting the eye longitudinally along the chart without confusion of lines, 80 it is convenient to distinguish alternate strips of the chart by shading, hatching, or coloration, as indicated by the parallel lines shown.

Longitudinally the chart is divided either 85 by curved lines *a* as in Fig. 1, or by straight lines *b* as in Fig. 2; these lines representing equal divisions of time; and in accordance with the usual practice the lines representing the greater divisions may be made 90 heavier than others. Thus in Fig. 1 the smaller divisions represent hours and the greater divisions periods of six or twelve hours each; while in Fig. 2 the smaller divisions are of five minutes each and the 95 greater divisions thirty minutes and one hour respectively, while the date is written at one edge of the chart. Naturally I do not limit myself to any particular number of divisions or spacing between the divisions, as this will be regulated according to the 100 minuteness desired in the record.

In using the chart, the registering-apparatus is so constructed as to cause the recording-point to pass over always an even number of strips, so that it cannot pass from a white strip to a colored or shaded one without passing through one of the poles; except that it can pass from north or south to either a shaded or plain strip, but after it 105 has passed the second strip from either of the extreme strips it must stop always on either the plain or shaded strips. For example the

recording-point can pass for instance from north-by-east to north or from south-by-west to south. This is illustrated by the specimen record *c* shown on Fig. 1 of the drawings.

From the above description it will be readily seen that my invention will assume a variety of forms, all embodying the same principles, and that a great number of changes and modifications are possible in the nonessentials without departing from the spirit of my invention, the scope of which is particularly defined in my claims.

Having thus described my invention, what I claim as new and desire to secure by Letters Patent is:

1. A chart for a recording-compass divided into a plurality of longitudinal strips corresponding to the compass-rhumbs and arranged with two opposite rhumbs on opposite sides thereof and the rhumbs to right and left of the rhumb-line joining said opposite rhumbs arranged alternately in serial order proceeding from one of said extreme rhumbs to the other extreme rhumb.
2. A chart for a recording-compass divided into a plurality of longitudinal strips corresponding to the compass-rhumbs arranged with the north and south rhumbs on opposite sides thereof and the intermediate rhumbs to right and left of the meridian arranged in alternate succession from north to south, symmetrical east and west rhumbs being adjacent to each other.
3. A chart for a recording-compass divided into a plurality of longitudinal strips corresponding to the compass-rhumbs and arranged with two opposite rhumbs on opposite sides thereof and the rhumbs to right and left of the rhumb-line joining said opposite rhumbs arranged alternately in serial order proceeding from one of said extreme rhumbs to the other extreme rhumb, alter-

nate strips being distinguished to the eye from the others as by coloring, shading or the like.

4. A chart for a recording-compass divided into a plurality of longitudinal strips corresponding to the compass-rhumbs arranged with the north and south rhumbs on opposite sides thereof and the intermediate rhumbs to right and left of the meridian arranged in alternate succession from north to south, symmetrical east and west rhumbs being adjacent to each other, the east bearings being distinguished to the eye from the west bearings, as by coloring, shading or the like.

5. A chart for a recording-compass divided into a plurality of longitudinal strips corresponding to the compass-rhumbs and arranged with two opposite rhumbs on opposite sides thereof and the rhumbs to right and left of the rhumb-line joining said opposite rhumbs arranged laterally in serial order proceeding from one of said extreme rhumbs to the other extreme rhumb, and a plurality of transverse lines corresponding to equal intervals of time.

6. A chart for a recording-compass divided into a plurality of longitudinal strips corresponding to the compass-rhumbs arranged with the north and south rhumbs on the opposite sides thereof and the intermediate rhumbs to right and left of the meridian arranged in alternate succession from north to south, symmetrical east and west rhumbs being adjacent to each other; and a plurality of transverse lines corresponding to equal intervals of time.

In witness whereof I have hereunto set my hand this 22 day of March, 1909.

EDWIN SCHUETTE.
